Assistant Examiner — Amanda Kay Birdwell

(74) *Attorney, Agent, or Firm* — Sheridan Ross P.C.

(57) **CLAIM**

The ornamental design for a bottle, as shown and described.

DESCRIPTION

FIG. 1 is a top view of a first embodiment of the bottle.

FIG. 2 is a bottom view of the bottle of FIG. 1.

FIG. 3 is a front view of the bottle of FIG. 1.

FIG. 4 is a back view of the bottle of FIG. 1.

FIG. 5 is a left-side view of the bottle of FIG. 1.

FIG. 6 is a right-side view of the bottle of FIG. 1.

FIG. 7 is a perspective view of the bottle of FIG. 1.

FIG. 8 is a top view of a second embodiment of the bottle.

FIG. 9 is a bottom view of the bottle of FIG. 8.

FIG. 10 is a front view of the bottle of FIG. 8.

FIG. 11 is a back view of the bottle of FIG. 8.

FIG. 12 is a left-side view of the bottle of FIG. 8.

FIG. 13 is a right-side view of the bottle of FIG. 8.

FIG. 14 is a perspective view of a third embodiment of the bottle.

FIG. 15 is a top view of the bottle of FIG. 14.

FIG. 16 is a bottom view of the bottle of FIG. 14.

FIG. 17 is a front view of the bottle of FIG. 14.

FIG. 18 is a back view of the bottle of FIG. 14.

FIG. 19 is a left-side view of the bottle of FIG. 14.

FIG. 20 is a right-side view of the bottle of FIG. 14.

FIG. 21 is a perspective view of a fourth embodiment of the bottle.

FIG. 22 is a top view of the bottle of FIG. 21.

FIG. 23 is a bottom view of the bottle of FIG. 21.

FIG. 24 is a front view of the bottle of FIG. 21.

FIG. 25 is a back view of the bottle of FIG. 21.

FIG. 26 is a left-side view of the bottle of FIG. 21; and,

FIG. 27 is a right-side view of the bottle of FIG. 21.

The broken lines shown illustrate portions of the bottle and form no part of the claimed design.

1 Claim, 23 Drawing Sheets
